UNITED STATES PATENT OFFICE

CARL P. SEYLER, OF PITTSBURGH, PENNSYLVANIA

INSULATOR SUPPORTING POST

Application filed February 16, 1927. Serial No. 168,617.

The invention has in view to provide means for supporting and fixedly holding an insulator on the terminal of a post, arm, or other similar supporting device. It consists of such a post or arm having on its outer end a resilient thread-engaging arbor, fixedly connected with the post and having external threads for engagement by the insulator, with means providing sufficient resiliency to effect tightening when the insulator is screwed upon the arbor, together with certain other features of construction and improvement as hereinafter described.

In the drawings, showing certain preferred embodiments of the invention:

Fig. 1 is a sectional view showing my improved support and an insulator carried thereby;

Fig. 2 is a partial view in elevation of the upper end of the post and its resilient threaded terminal;

Figs. 3 and 4 are perspective views, showing the two halves of the resilient mounting, before attachment to the post;

Fig. 5 is a cross-section on the line V—V of Fig. 2;

Fig. 6 is a view of the upper end of the post before the screw attachments are applied thereto;

Fig. 7 is a plan view of the outer end of the post;

Fig. 8 is a sectional view, showing a modified construction of arbor, with a separate resistance terminal piece;

Fig. 9 is a plan view of Fig. 8;

Fig. 10 is a detail view of the resistance terminal piece;

Fig. 11 is a view in elevation similar to Fig. 2, showing a further modified construction made of a continuous one-piece blank; and

Fig. 12 is a plan view of Fig. 11.

Referring to the construction shown in Figs. 1 to 7 inclusive, the supporting post or arm 2, preferably made of a forging or steel casting, is adapted to be mounted by its flared base 3 on any suitable supporting carrier, as an angle member 4, and tightened thereon by one or more nuts 5, engaging a central threaded stem 6.

At its upper end, the post 2 is annularly

reduced, as at 7, between a lower shoulder 8 and an upper collar 9, providing clearance for inward compression of the threaded sheet metal arbor members 10—10.

These members, as shown in Figs. 3 and 4, are made in halves, having lower securing semi-circular shell or base portions 11 and upper threaded portions 12. These members are easily made from suitable blanks by pressing in dies to form the semi-circular threads and attaching portions.

The threaded portion is somewhat larger in diameter than the shell portion and tapers slightly from its base to the top, so that, when placed together around the lower portion of the reduced shank 7, the threaded extensions embrace the shank with intervening clearance, and bear against or lie adjacent to the terminal collar 9.

Lower semi-circular shell portions 11 are welded to the lower portion of reduced shank 7, and to each other, by the usual electric welding operation, or by soldering, as indicated at 13. If desired, the connection may be also made by one or more rivets 14, and either or both of such connecting means may be utilized.

When thus placed together, the two semi-circular shell portions 12 are slightly spaced apart, between their adjacent edges as at 15, and with their upper terminals in approximate bearing relation to the collar 9.

As thus mounted, the threaded arbor is in position for receiving the insulator 16, of any suitable construction and having the usual interior threads for screwing thereon. As the insulator is advanced over the threads, it tends to bind the arbor members which are sufficiently resilient to be pressed together, between their lower and upper terminals, so as to effect tight binding engagement with the insulator, and to hold it permanently in position against loosening.

The upper end of the post 2, above collar 9, is also preferably provided with an outwardly extending button or ridge 17, against which the inner end of the insulator may come into contact, to limit further movement, so as to avoid breakage under undue strain. Such bearing also tends to act in the nature

of a nut lock, preventing any tendency to loosen.

In Fig. 8, I show a slightly modified construction in which the two semi-circular base portions 11a are fitted around the reduced portion 7 of the post 2 and welded together and thereto in the manner described. The side portions 12a embodying the thread members extend upwardly beyond such attachment or connection, with the intervening clearance space 15a, and are rounded over the upper edge of the terminal 9a of the stem. Such terminal, however, is left plane across its top, and for the purpose of providing a limiting stop for the insulator, I insert underneath and between the oppositely inwardly turned lip terminals 10a of each side member, the resisting terminal piece 17a. Such piece is made of a pressed blank of sheet metal in the form shown in Fig. 10, fitting freely between the resilient ends of the threaded members and extending upwardly therebeyond for contact with the inner middle portion of the insulator, in the same manner as shown in Fig. 1.

In Figs. 11 and 12, I show a further modified construction in which the attaching base or shell portions 11b are welded around the reduced base portion of stem 7 of post 2, as clearly shown. The side threaded members 12b tapering toward the end and spaced outwardly from the supporting stem, are separated by the clearance slot 15b, and are joined at the top by the connecting integral upwardly extending bridge member 17b. Such member, as shown, projects beyond the end of the threaded portion, providing the insulator arresting abutment with resulting binding on the threads, in the same general manner as already described.

The construction and operation of the device will be readily understood and appreciated by all those familiar with the general class of insulator supports. It is extremely cheap, serviceable and efficient in construction and use, and when protected by the insulator, is not subject to rust or weather deterioration.

It will be understood that the invention may be utilized in connection with any suitable design of support, and also may be erected in a vertical or any other desired position. It may be changed or varied by the skilled mechanic in size, design, or other details, and all such changes are to be understood as within the scope of the following claims.

What I claim is:

1. In combination with a supporting arm having an outer enlarged circular terminal collar, an insulator support having a threaded sheet metal arbor consisting of two spaced apart semi-circular threaded portions fixedly mounted on the supporting arm and bearing by their outer circular embracing ends

against a substantial portion of said collar with an inner compressible portion.

2. In an insulator support, the combination with a supporting post having a terminal collar extending laterally beyond the shank portion and a separable endmost abutment for limiting engagement with an insulator, of a two-part threaded arbor bearing against the collar at its outer end and fixedly connected at its inner end with the post and spaced apart by oppositely located clearance slots.

In testimony whereof I hereunto affix my signature.
